WIRE CRIMPING MACHINE

Joseph R. Guess, El Monte, Calif.

Application May 19, 1947, Serial No. 748,926

2 Claims. (Cl. 140—105)

1

This invention relates to machines for crimping wire such as is adapted to be woven into screens.

The wires or rods used in heavy screens employed for screening gravel and like material are of such large cross-section that it is necessary to preform them before the screen is woven. Heretofore, this was accomplished by an intermittent one-revolution press operation. While the use of punch presses is satisfactory insofar as the resultant article is concerned, they are relatively slow and for facility in handling the material, entailed pre-cutting the same into lengths. Die-struck crimping, such as formed by a punch and die, causes a weakening stretch in the rod or wire frequently resulting in fissures with a resulting loss of strength in the same.

An object of the present invention is to provide a wire crimping machine which performs its function with a rolling action so that the crimps are each gradually and progressively formed to cause a gradual stretch at the crimps and thereby obviating rupture such as caused by die-struck means.

Another object of the invention is to provide a wire crimping machine which has a rolling mill action whereby the operation is continuous rather than intermittent and enabling the handling of wire from a roll thereof when suitably fed from a free running reel.

Another object of the invention is to provide novel and improved crimping rolls and to provide simple and effective means for adjusting said rolls relatively to each other.

A further object of the invention is to provide improved means for guiding the wire on both sides of the crimping rolls and to make said means adjustable with respect to the faces of the rolls so that the crimping can be accomplished at various portions of said faces to, thereby, reduce wear on the rolls.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views,

2

Fig. 1 is a partially broken end elevational view of a wire crimping machine embodying features of the invention.

Fig. 2 is a side elevational view thereof.

Figs. 3 and 4 are enlarged fragmentary views showing successive wire crimping positions of the crimping rolls.

Fig. 5 is an enlarged cross-sectional view as taken on the line 5—5 of Fig. 2.

10 The wire crimping machine which is illustrated comprises, generally, a machine frame 10, a pair of parallel shafts 11 and 12 mounted in the frame, means 13 connecting the shafts to rotate oppositely, means 14 to drive said shafts,

15 wire crimping means 15 carried by the shafts, wire guiding means 16 carried by the frame and adjustable relative to the crimping means 15, means 17 for effecting accurate alignment of the crimping means, and means 18 for adjusting one 20 shaft with respect to the other.

The frame 10 comprises spaced end standards 19 connected, near their bottoms, by a vertical member 20 and, thereabove, by a horizontal member 21. These parts are suitably connected

25 by welding to form a rigid frame structure. The frame further includes a bracket 22 which extends outward from one of the standards 19, a shaft journal 23 on the end of said bracket and a similar journal 24 mounted on member 20. The drive means 14 is mounted on said journals 23 and 24.

A journal bearing 25 is carried by each standard and said bearings are aligned to receive the shaft 11. The upper end of each standard is 35 formed with a seat 26 and in each seat, slidably engaged therein, there is provided a journal bearing 27 for the shaft 12. A cap member 28 is secured to the top of each standard and each is provided with a threaded vertical passage 29 in alignment with the respective bearings 27.

The means 13 interconnects shafts 11 and 12 and comprises a gear 30 on shaft 11 and a similar meshing gear 31 on shaft 12. The latter gear is fixedly connected to its shaft.

40 The drive means 14 comprises a shaft 32 mounted between the journals 23 and 24, a pulley 33 on said shaft driven from any suitable means such as an electric motor, a clutch 34 on said shaft, and a drive, such as gears 35 and 36 connecting shafts 32 and 11. With the clutch 34 engaged, rotation of pulleys 33 results in rotation of shafts 11 and 12 in opposite directions.

The wire crimping means 15 comprises a pair of rolls 37 and 38 on the respective shafts 11 and 55 12, said rolls being removably mounted on extensions of said shafts outward of the standard 19 which is opposite to the standard carrying

bracket 22. Each roll is made of hardened steel and with a generously wide cylindrical surface and, in practice, these surfaces are roughened or knurled as at 39.

The roll 37, around its periphery, is formed with a plurality of similar, uniformly spaced concave seats 40 each formed with a curvature somewhat deeper than the curvature of the crimps to be formed in the wire. Between adjacent seats 40, the roll 37 is formed with milled transverse slots 41 for hardened rectangular die members 42. Each of the latter extends, as at 43, above the surface of the roll and each extension is curved, as shown, for the purpose of forming a series of uniformly spaced indentations 44 in a wire passing between the rolls. The members 42 are snugly fitted in slots 41, will retain their position therein and yet are readily removable for replacement.

The roll 38 around its periphery and spaced in accordance with the spacing of the seats 40, is formed with a plurality of slots 45 for hardened crimping members 46, each of which projects uniformly beyond the surface of said roll and is formed with an outer curved edge 47. The degree of projection is determined by the size of the wire and the depth of the crimps to be formed in said wire. The crimping members 46 are similar to the members 42 and are held in place in a similar manner.

It is evident that a wire, passed between the rolls, as the latter are driven as indicated, will be fed by the knurled surfaces of said rolls; that, as shown in Fig. 3, each of the crimping members 46, successively, will stretch spaced parts of the wire W to force the same into aligned seats 40 to form a series of offsets or crimps 48 in said wire; that the curved edge 47 of the crimping members 46 will indent each crimp at 49 as the latter is being formed; and, as shown in Fig. 4, the curved ends 43 of members 42 will indent the wire W on the opposite side thereof at 44 midway between adjacent crimps.

It will be noted that the forming of the wire is continuous and the crimps are formed without restricting the wire on opposite ends thereof. The metal is thus free to flow during crimping to obviate cranks and fissures therein. The crimps 48, of course, locate cross wires of a screen and the indentations 49 and 50 effect accurate inter-lock of the warp and weft wires to provide a screen whose mesh is uniform throughout.

From Fig. 2 it will be seen that the surfaces of the rolls are of generous width so that the wire can be passed therebetween centrally or nearer either side, as desired, and thereby to give increased life to the rolls. Accordingly, the means 16 is made adjustable to guide the wire during forming thereof. Said means 16 comprises a guide bracket 50 on the incoming side of the rolls, a similar guide bracket 51 on the opposite side, and adjustable mounting means 52 for each guide bracket so that the same may be aligned with the rolls and also adjusted laterally for guiding the wire along a desired path between the rolls. Suitable bosses 53 are provided on the machine frame 10 for mounting brackets 50 and 51. The bracket 50 is provided with a hardened bushing having a circular hole 54 to guide the wire and the bracket 51 is provided with a bushing having an elongated hole 55 to allow passage therethrough of the crimps 48.

The means 17 is provided for effecting proper alignment of the rolls 37 and 38 so that the seats 40 and crimping members 46 are suitably related

with a minimum of back-lash play in gears 30 and 31. To this end, gear 30 is mounted for free rotation on shaft 11, the hub 56 of said gear is provided with a pair of spaced outwardly and forwardly extending lugs 57, a collar 58 is fixed to the shaft, an extension 59 of said collar is arranged between lugs 57, and a set screw 60 is carried by each lug 57 and directed to impinge on opposite sides of extension 59. By manipulation of the set screws, an angular relative adjustment of the shaft 11 and gear 30 may be obtained for the purposes indicated and said adjustment will be maintained by the opposed locking action of the set screws with respect to each other.

The machine is designed to handle wire varying in diameter by providing the means 18 for adjusting the rolls relatively. In this instance, roll 37 and its shaft 11 are carried by the fixed journal bearings 25. The roll 38 and its shaft 12 are carried in the journal bearings 27. The means 18 is provided for adjusting both bearings simultaneously to move roll 38 toward and from roll 37, as desired. Said means comprises a threaded stem 61 in each threaded seat 29 of the caps 28, a T-head connection 62 between each stem and its respective journal bearing 27, and a chain and sprocket connection 63 between the stems. A polygonal end 64, on one stem 61, is provided for a tool whereby said stem is rotated to cause similar rotation of the other stem, and simultaneous vertical adjustment, in threads 29 of said stems and, consequently, of the shaft 12, and roll 38. A nut 65 is provided on one stem to lock the means 18 after adjustment.

Means are provided for operating clutch 34 from a position adjacent the crimping rolls. As shown, said means comprises a clutch collar 66 on shaft 32 for engaging clutch actuating lugs 67, a lever 68 for sliding the collar, a link 69 extending from lever 68, and a clutch lever 70, fulcrumed at 71, on the frame 10 for effecting shifting of collar 66. Suitable stop means 72 are associated with the clutch lever to limit its movement in either direction. A handle 73 on the clutch lever is located so that an attendant facing rolls 37 and 38 can readily operate clutch 34 to start or stop the drive 14.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a machine of the character described, a pair of interconnected driven rolls for forming a continuous length of screen wire having uniformly spaced curved and offset crimps along the length thereof, an indentation in the concave side of each crimp and a similar indentation in the wire between crimps and on the opposite side of the first mentioned indentations, one of said rolls having radially extending and uniformly spaced projections and the other having commensurately spaced concave seats into which said projections extend, said projections and seats cooperating to form the mentioned curved crimps and the indentations therein, the roll having the seats being provided with projections alternating with said

seats for forming the other indentations, and the peripheral faces of said rolls being knurled to effect non-slipping gripping of the wire therebetween to maintain uniformity of the spaces between the crimps and between the intermediate indentations.

2. A wire crimping machine comprising a pair of rolls for passing a wire between them, one of said rolls having uniformly spaced peripheral concave seats, a projection on the peripheral face of said roll between each pair of adjacent seats to form a series of spaced indentations in said wire, a series of projections on the peripheral face of the other roll adapted to enter the seats of the first-mentioned roll successively, and means for driving the rolls continuously whereby a series of crimps offset from said indentations are formed in the wire by said projections deforming the wire into the seats.
